CLAIM

The ornamental design for a display screen with icon or packaging with surface ornamentation, as shown and described.

DESCRIPTION

FIG. 1 is a front view of a first embodiment of a display screen with icon or packaging with surface ornamentation; FIG. 2 is a front view of a second embodiment of a display screen with icon or packaging with surface ornamentation; FIG. 3 is a front view of a third embodiment of a display screen with icon or packaging with surface ornamentation; FIG. 4 is another front view of the first embodiment of the display screen with icon or packaging with surface ornamentation shown in FIG. 1, but with alternate unclaimed subject matter;

FIG. 5 is another front view of the second embodiment of the display screen with icon or packaging with surface ornamentation shown in FIG. 2, but with alternate unclaimed subject matter; and,

FIG. 6 is another front view of the third embodiment of the display screen with icon or packaging with surface ornamentation shown in FIG. 3, but with alternate unclaimed subject matter.

The broken lines are included for the purpose of illustrating environmental structure and form no part of the claimed design.

1 Claim, 2 Drawing Sheets
